CLAIM

The ornamental design for a pair of motorcycle body shells, as shown and described.

DESCRIPTION

FIG. 1 is a right side elevational view of the pair of motorcycle body shells with a motorcycle shown in broken lines which forms no part of the claimed design.

FIG. 2 is a left side elevational view of the motorcycle body shell.

FIG. 3 is an exploded top plan view of the right and left side motorcycle body shells of the pair of motorcycle body shells.

FIG. 4 is an exploded front elevational view of the right and left side motorcycle body shells of the pair of motorcycle body shells; and,

FIG. 5 is an exploded rear elevational view of the right and left side motorcycle body shells of the pair of motorcycle body shells.
